UNITED STATES PATENT OFFICE.

ANDREW FRANCIS NEY, OF EAST KEW, VICTORIA, AUSTRALIA.

CARTON-FILLING MACHINE.

Application filed June 29, 1923, Serial No. 648,549, and in Australia July 19, 1922.

The present invention refers to machines for filling granular or powdered material which is sometimes moist into cartons of the usual rectangular form, with either a fixed or folded bottom and the top closed by two or four flap pieces, a pair of which approach and may slightly overlap each other and are covered by a third flap piece having a central slit into which the end of the remaining and fourth flap usually tapered is inserted, or in the case of only two flaps only the latter function is necessary.

Various machines are in use for effecting the filling of cartons principally of the weighing machine type which delivers a weighed quantity into a carton held beneath the delivery outlet by an attendant and which machine automatically cuts off supply as soon as each quantity of equal weight is measured for delivery.

The present invention eliminates the complications involved in the weighing machine type, and is particularly adapted to deal with more or less moist material such as jelly crystals. Furthermore, the filling apparatus according to this invention is so contrived that a clear passage is provided for the feed of moist material which in the known machines is hampered by the intervention of stirring devices, which with the present invention are unnecessary.

Briefly stated the machine according to the present invention provides for delivery of the granular material from a vibratory hopper to an underlying series of pockets circumferentially arranged about a common centre which pockets when filled each register in succession with one of a number of empty cartons which are successively brought into position for such registration by an endless chain fitted with receptacles to receive said pockets.

In conjunction with said hopper, series of pockets, and receptacles for the cartons, mechanism is provided for opening the cartons, after they are deposited in the receptacles, by flattening out the closing flaps and retaining the latter in open flat position during travel of the cartons to filling position. Means are also provided for emptying the pockets to insure the filling of the cartons and for removal of any material adhering to the walls of the pockets. Mechanism for performing the necessary movement of the flaps after filling, to close the

cartons, and finally further means for ejecting the filled and closed cartons from the machine are provided.

These several functions in ordered sequence are automatically performed in a practical and positive manner by the mechanisms hereinafter described with reference to the accompanying drawings which depict a practical application of the invention.

In these drawings which illustrate a machine for filling small cartons with a uniform quantity of jelly crystals for example,

Fig. 1 is a plan and

Fig. 2 a side elevation of the machine,

Figs. 3, 4, 5 and 6 are vertical sections respectively on lines III—III, IV—IV, V—V, VI—VI of Fig. 1,

Fig. 7 is a vertical section on line VII—VII of Fig. 6.

Fig. 8 is a vertical section on line VIII—VIII of Fig. 1.

Figs. 9 and 10 are enlarged sectional views illustrating the last operations of interlocking the flaps of the cartons.

Fig. 11 is a view of the filled and closed carton.

Fig. 12 is a vertical section on line XII—XII of Fig. 1.

On the base plate B is movably mounted an endless carrier 21 consisting of a series of hinged links 1, formed with laterally arranged receptacles P having opposite interior end walls flared near the top as indicated at 2, 2, Fig. 9. Said receptacles are closed at their bottoms by the base plate B and are movable between vertical parallel guide plates 3, arranged longitudinally of the base plate.

The carrier engages sprockets 4, 5, rotatably mounted near each end of the base plate, said sprockets having substantially octagonal peripheries formed with grooves 107 to engage the hinge pins 108 which connect the links 1, sprocket 4, being idle and fixed to a spindle 6 rotatably mounted in the base plate while the spindle 7 of sprocket 5 is similarly journaled and provided on its lower end with a ratchet wheel 8.

The latter is engaged by a spring controlled pawl 9 on a longitudinally reciprocated rod 10 journalled in bearings 11 and provided with a roller 12 engaging a slotted cam 13 on the shaft 14 driven by suitable gear 15 by a pulley 16. The rotary movement of the shaft 14, through the medium of

cam slot 13 and roller 12 imparts a reciprocating movement to the rod 10. During the movement of the latter to the left, the pawl 9 engages the ratchet 8 so that the spindle 7 is rotated during said movement. On the return movement of the rod 10, the pawl 9 rides idly on the ratchet so that the spindle 7 remains stationary; thus an intermittent movement is imparted to the chain carrier 10 and sprockets.

The cartons C are hand fed into the pockets P at the front of the carrier about the position F, Fig. 1, with their flaps 17, 18, 19 and 20 approximately lying back flat but 15 usually slightly raised, flap 19 having a slit 22 and flap 20 being preferably peaked or tapered.

The first operation necessary is to ensure the flaps being laid flat back in open position and this is performed by a horizontal plate 23 located loosely above the tops of the pockets. The plate is tapered at one end as at 24 (Fig. 3) and formed with a broad straight edge 25 (Figs. 1 and 3) at the opposite end both ends being slightly declined. The plate is fixed to a slide or bridge 26 slidably mounted at its ends on parallel horizontal guide bars 27 fixed to short standards 28 on the base plate.

30 The slide 26 is connected to a lever 29 by a link 30 and said lever is fulcrumed on shaft 33 pivoted on brackets 234 and 235 and is formed with a longitudinal slot 31 engaged by a pin 32 projecting from the reciprocating bar 10.

As the rod 10 moves backwardly in the direction of the arrow in Fig. 3 the pin 32 moves the lever 29 in the same direction and causes the tapered end 24 of plate to engage 40 the adjacent flap 17 of a carton and cause it to turn into the position shown by the preceding flap in Fig. 3. When the cartons are placed in the pockets, the flaps do not lie flat, but are flared outwardly at an angle so 45 that as plate 23 moves backward the end 24 gets under the flap 17 and engages it and turns it over to approximately the opposite angle, it being so maintained while the carton is passing under the plate. By continued motion of the plate the end 24 engages 50 the opposite flap 18 and turns it back flat as in said figure and similarly the end 24 by reason of its gradually increasing width turns the flaps 19 and 20 back flat.

55 The carton carrier advances with the flaps maintained as described until the flap 17 is freed from the straight end 25 and by the inherent spring in the usual cardboard or paper employed for making cartons said 60 flap 17 rises slightly. Thus when the plate 23 moves in the direction of the carrier the plate by reason of its lever moves quicker than the carrier and its edge 25 engages the flap 17 and turns it back flat and by the advancement of the carrier this flap and like-

wise in succession the flaps 19, 20 and 18 are transferred from under plate 23 to beneath the projecting end 83 of the plate 34 fixed to standards 35 on the base plate B. The end 83 is upwardly inclined and dished as at 61 70 (Fig. 3) in its centre and the slide 26 is correspondingly dished as at 62 (Fig. 1).

The plate 34 is curved correspondingly to the curve of the carrier around sprocket 5 and it separates the carrier from a circumferentially arranged series of superposed measuring pockets 135 (Figs. 1 and 6). These pockets, which are open at each end, are fixed to the flange 104, Fig. 4, of a circular plate 105 fixed on spindle 7 and covered by a plate or cover 36 formed with openings 37 coincident with two pockets 135. Above the plate 36 is a hopper 38 into which the material is fed, preferably capable of filling two measuring pockets 135 at a time said 85 pockets being closed at the bottom by the curved plate 34.

As the measuring pockets 135 advance at the same rate as the carton carrier, the bottom edge of the hopper trims the material 90 across the top edge of said pockets so that each pocket contains the same quantity of material.

In order to prevent a choke of the material in the hopper 38 and ensure its feed by 95 gravity into the measuring pockets said hopper is pivoted at one end upon a standard 39 on the base plate and a projecting arm 40 on the other end of the hopper is provided with a roller 41 engaging a cam 42 rotatable on a 100 spindle 43 and driven by pulley 44 belt 45 and pulley 46 on the main shaft 14.

The cam is formed with a wavy edged groove that imparts a horizontal vibratory motion to the roller 41 and consequently to 105 the hopper which ensures delivery of material therefrom into the measure pockets.

At a further advanced point the stationary plate 34 is formed with a rectangular opening 47 through which a measure pocket 135 transfers its contents into a co-incident carton C while the carrier is momentarily stationary.

In order to ensure complete discharge a vertical plunger 48 is provided, Figs. 1, 2 115 and 6, the shank of which is mounted on an arm 49 projecting from a vertical reciprocating rod 50 journalled in a bracket 51 on the base plate and guided at its lower end in a vertical guide 52 and a side plate 53. The rod 50 Fig. 5 is connected by a pin 54 with a slot 55 of a lever 56 pivoted at 57 on a bracket 58 and provided with a roller 59 engaging a cam 60, on the main shaft. Vertical reciprocation of the plunger 48 120 completely through the measuring pocket and the opening 47 ensures the entire contents of the pocket being delivered to the carton beneath.

In order to ensure correct registration of 130

the measure pocket with the carton being supplied therefrom the carrier is held stationary by means of a vertically reciprocating stop 63 Figs. 6 and 7 operating in a slot 64 formed in the base plate.

The stop has at its lower end a pivoted block 65, Fig. 6 engaged by the bifurcated end of a lever 66 fulcrumed at 67 on bracket 68 supported by a spring 69 said lever having a roller 70 engaging a cam 71 on the main shaft 14.

The stop 63 rises through slot 64 in front of the pocket P of the carrier containing the carton receiving the contents of a measure pocket and ensures registration of the sides of the measure and carton pockets. The inner upper end 72 of the stop is preferably bevelled or slightly curved (see Fig. 7) and engages the link 1 in front of said stop if same should be extending outwardly and so pushes it back with the object of ensuring exact registration of front and rear sides of the carrier pockets with the corresponding sides of the measure pockets.

Upon the rod 50 is another arm 73 supporting the shank of a rectangular cleaning brush 74 that reciprocates vertically in each measure pocket in succession and discharges any material remaining in said pockets into a receptacle 75, Figs. 1 and 5.

The mechanism for closing down the flaps of the filled cartons as shown in Figs. 1 and 6 forms the subject matter of my divisional application Serial No. 739,226, filed Sept. 22, 1924, and comprises a fixed narrow overhead longitudinal plate 76 mounted on a bridge fixed to standards 77 and a horizontally reciprocating finger or folder 78. The latter operates in guides 82 on plate 34 and is pivoted on an arm 79 pivoted on a vertical lever 110 on the rock shaft 33 which latter at an end has an arm 80 formed with a lateral slot 81 engaged by the pin 32 on the reciprocating rod or bar 10.

As the carton advances the end of plate 76 engages the flap 17 and turns it inwardly to an angle approximately 30 degrees to the horizontal, then the folder 78 advances and its end engages flap 18 and turns it into horizontal position. When the carton continues, plate 76 presses flap 17 down over flap 18 and the other flaps 19 and 20 are engaged respectively by overhead inclined arms 84, 85 Fig. 1, which arms converge and the arm 84 is bent to complete its folding operation before arm 85 functions so that the peaked flap 20 is the one overlying the other three flaps.

The final operation being the depression of the flap 19 with the slit 22 and the peaked flap 20 to finally lock the peak in the slit. This operation is performed by a downwardly bent finger 86, Figs. 8, 9, and 10 on an arm 87 pivoted on standards 89 and connected to a vertical rod 88 spring controlled

and connected with an approximately horizontal arm 90 having a roller 91 engaging cam 92 on the shaft 14.

The point of the finger 86 in depressing the slotted flap and the peaked flap moves towards the inner side as in Figs. 9 and 10 and in doing so its peak is flipped over the outer edge 112 of the slit 22 and into the latter so that when the finger rises the peak of the flap 20 progresses further into said slit and so securely closes the filled carton. During this action the front and rear sides of the cartons are momentarily pressed outwardly, such movement being permitted by the extra width provided in the pockets by the flared mouth 2 thereof and the release of the finger permits the carton to resume its shape and thereby assist the peak to enter the slit 22.

The carton as shown in Fig. 11 then moves a step forward and is pushed through a slot 92, Fig. 12, formed in the base plate by a discharge plunger 93 the shank of which is mounted on a vertically reciprocated spring controlled rod 94 working in a vertical guide 95 and cover plate 139 and connected by a pin 96 and slot 97 with an arm 98 pivotally mounted on a bracket 99 and provided with a roller 100 engaging a cam 101 on the main shaft. The cartons discharged through opening 92 are delivered into a chute 102 leading to the packers.

It will be seen from the foregoing that the cartons having flap closure pieces are fed by hand to the pockets P on carrier 21 the flap pieces laid flat at plate 23 position (Fig. 1) and maintained flat until the cartons are filled at plunger 48 position then closed by plates 76 and 78 and levers 84 and 85 and finally by finger 87.

Further the granular material passes from the vibratory hopper 38 to the circumferentially arranged measure pockets 135 which latter when filled register with and empty into the cartons in succession.

Finally the filler and closed cartons are ejected from the pockets P by the plunger 93.

Also the measure pockets 135 are swept clean by the brush 74.

As a consequence the whole of the functions specified as constituting the objects of the invention are effected.

I claim:

1. A carton filling machine comprising an endless series of pockets for the reception of cartons, means for imparting an intermittent movement to the pockets, a series of bottomless pockets mounted above the carton pockets, and movable synchronously with the latter, a stationary plate interposed between the two series of pockets and having a discharge aperture therein, a stop movable into the path of the carton carrying pockets, and means to intermittently actuate said stop.

2. A carton filling machine comprising a base plate, an endless series of pockets for the reception of the cartons, means for intermittently moving the pockets along the base plate, a fixed plate having a discharge aperture therein mounted above the pockets, a series of superposed bottomless measuring pockets mounted above the plate, means for moving the measuring pockets synchronously with the carton pockets, a hopper for filling the measuring pockets, a vertically reciprocal stop, means to intermittently move the latter into the path of the carton pockets, a vertically movable plunger, and means to intermittently move the latter through the measuring pockets and the discharge aperture.
3. A carton filling machine comprising a base plate, an intermittently movable carrier traversing the plate and having a series of pockets for the reception of the cartons, a sprocket for moving the carrier, means for intermittently rotating the sprocket, a circular series of bottomless measuring pockets mounted above the carrier and movable with the sprocket, a hopper for supplying material to the measuring pockets, a plate interposed between the latter and the carrier and having an aperture therein at one end to permit the discharge of the material from the measuring pockets, a plunger mounted above said aperture, means to move the plunger through the measuring pockets and aperture, and means operated by the plunger operating means for cleaning the measuring pockets.
4. A carton filling machine comprising a base plate, an endless carrier traversing the latter having a series of holders for the cartons, sprockets engaging the carrier, a spindle carrying one of the sprockets, a driving mechanism for intermittently rotating the spindle, including a rotary driving shaft, a series of measuring pockets mounted above the carrier, means connecting the pockets to the spindle whereby said pockets are moved synchronously with the carrier, means for supplying material to the pockets, a plate interposed between the latter and the carrier having a discharge aperture therein, a stop movable into the path of the carrier, and a cam on the driving shaft for intermittently actuating the stop, whereby the carton holders are accurately positioned relatively to the aperture.
5. A carton filling machine comprising a base plate, an endless carrier traversing the latter having a series of holders for the cartons, sprockets engaging the carrier, a spindle carrying one of the sprockets, a driving mechanism for intermittently rotating the spindle, including a rotary driving shaft, a series of measuring pockets mounted above the carrier, means connecting the pockets to the spindle whereby said pockets are moved synchronously with the carrier, means for supplying material to the pockets, a plate interposed between the latter and the carrier having a discharge aperture therein, a stop movable into the path of the carrier, a cam on the driving shaft for intermittently actuating the stop, whereby the carton holders are accurately positioned relatively to the aperture, a vertically reciprocal rod extending through the base plate, an arm on said rod, a plunger carried by the arm above the aperture, a cam on the driving shaft, and a lever actuated by the last named cam for reciprocating said rod.

Dated this 18th day of May, 1923.

ANDREW FRANCIS NEY.
